VARIABLE CONDENSER

Ferdinand Julius W. Schoenborn, Riverhead,
N. Y., assignor to Radio Corporation of America,
a corporation of Delaware

Application October 25, 1939, Serial No. 301,107

5 Claims. (CL 175—41.5)

This invention relates to a new and improved variable condenser.

An object is to provide an extremely accurate variable condenser for use with ultra high frequencies.

Another object is to provide a variable condenser for use with a short wave radio receiver.

Still another object is to provide a variable condenser which will maintain extremely accurate capacity calibration, regardless of temperature changes.

A further object is to provide a variable condenser which eliminates noisy performance and capacity effect during operation of the unit.

A feature of this invention is the insulated variable electrode with brush contacts to ground at one point only.

Another feature of this invention is the compact arrangement of the component parts and the ease with which they are assembled.

Still another feature is the novel scale illumination and adjustment of the light.

This invention will best be understood by referring to the accompanying drawing, in which:

Fig. 1 is a longitudinal section of the variable condenser of this invention;

Fig. 2 is a cross section of Fig. 1; and

Fig. 3 is a front elevation of Fig. 1.

Referring now in detail to the drawing, a fixed

hollow electrode 1 is secured by press fit into a concentric ground Isolantite insulating support bushing 2, the latter being also fastened into a

tubular metallic casing member 3. A flange 4 being part of casing 3 supports it to a panel 5

of a radio receiver, the forward end of casing 3 is threaded to receive a threaded end cap 6

which clamps a bushing 7. A standard machinists' micrometer head 8, has its spindle 9 terminating in a pressed-on Isolantite bushing 10 which

also acts as a stop for the variable electrode. A silver shaft 11 forms the other or variable electrode secured by press fit to bushing 10. A variable electrode support barrel 12 is threaded to

bushing 7 and accurately maintains variable electrode 11 concentric with fixed electrode 1. A jewel-like bushing 13 of "Pyrex" glass mounted

concentric in support barrel 12 provides an insulated bearing for variable electrode 11 and reduces wear on said electrode to a minimum.

To aid in providing quietness of performance, a pair of beryllium copper, silver tipped, brush members 14 are secured at a point of entrance to support barrel 12. Members 14 also maintain the variable electrode 11 at ground poten-

tial. A terminal 15 connects the fixed electrode 1 to the high potential side of the radio receiver. A split strap member 16 is arranged to surround the outside end of casing member 3 and supports a light shield 17 which is clamped thereon by means of a screw 18 and nut 19. Illumination on the micrometer scale is maintained by means of a lamp bulb 20, the light rays of which pass through a narrow slit 21.

10 Although only one embodiment of this invention is shown, it is to be distinctly understood that the invention should not be limited precisely thereto.

What is claimed is:

15 1. A variable vernier condenser comprising a metallic casing member, a glass tube bearing located concentric within said casing, a tubular insulator secured to one end of said casing and projecting beyond said casing end, a tubular fixed electrode secured to the projecting portion of said insulator, a movable electrode secured to said casing at an end opposite said fixed electrode, and means to vary the condenser capacity by moving said movable electrode within said glass tube bearing and said fixed electrode.

20 2. A variable vernier condenser comprising a metallic casing member, a "Pyrex" glass tube bearing located concentric within said casing, a tubular insulator secured to one end of said casing and projecting beyond said casing end, a tubular fixed electrode secured to said insulator, a movable electrode secured to said casing at an end opposite said fixed electrode, and means to vary the condenser capacity by moving said movable electrode within said "Pyrex" glass tube bearing and said fixed electrode.

25 3. A variable vernier condenser comprising a metallic casing member, a tubular insulator secured to one end of said casing, a tubular fixed electrode secured to said insulator and concentric with said casing, a support barrel for said movable electrode secured to said casing at an end opposite said fixed electrode, a pair of contact springs and a "Pyrex" glass bearing secured to said support barrel at one end, a silver electrode movable in said glass bearing concentric with said casing, a tubular insulator secured to said electrode, a silver shaft secured to said insulator, a fixed threaded member secured to said support barrel at an end opposite said glass bearing, said shaft mounted in said fixed threaded member to provide the means to vary the condenser capacity by moving said movable electrode in and out of said fixed electrode.

4. A variable condenser comprising a tubular metallic casing, a fixed tubular electrode, a tubular insulating support member secured to the inside of said casing, said fixed tubular electrode secured to said insulating support member at one end thereof, a shaft-like movable electrode insulatingly supported within said casing, means including a threaded shaft to vary the condenser capacity, a tubular insulating bushing interposed between one end of said shaft-like movable electrode and said threaded shaft and secured thereto, projecting abutments within said casing, said tubular insulating bushing positioned on said threaded shaft and cooperating with said abutments to limit the motion in both the maximum and minimum capacity position of said condenser.

5. A variable condenser comprising a tubular metallic casing, a fixed tubular electrode, a tubu-

lar insulating support member secured to the inside of said casing, said fixed tubular electrode secured to said insulating support member at one end thereof, a shaft-like movable electrode insulatingly supported within said casing by an insulating tubular bearing member located concentric within said casing, means including a threaded shaft to vary the condenser capacity, a tubular insulating bushing interposed between one end of said shaft-like movable electrode and said threaded shaft and secured thereto, projecting abutments within said casing, said tubular insulating bushing positioned on said threaded shaft and cooperating with said abutments to limit the motion in both the maximum and minimum capacity position of said condenser.

FERDINAND JULIUS W. SCHOENBORN.
